United States Patent Office

Des. 224,387
Patented July 25, 1972

224,387

BENCH OR THE LIKE

Richard G. Reineman, Balboa, Calif., and George E. Schaefer, Muskegon, Mich., assignors to The Brunswick Corporation

Filed Nov. 20, 1970, Ser. No. 26,084

Term of patent 14 years

Int. Cl. D6—02

U.S. Cl. D6—58

Fig. 1

Fig. 2

Fig. 3

FIG. 1 is a perspective view of the bench of our design taken from the above left and to the front.

FIG. 2 is a top view of the bench of our design.

FIG. 3 is an end view of the bench of our design.

FIG. 4 is a front view of the bench of our design.

The appearance of the base in the rear is substantially similar to the front but planar.

We claim:

The ornamental design for a bench or the like, substantially as shown and described.
